UNITED STATES PATENT OFFICE.

HORACE M. CAKE, OF PHILADELPHIA, PENNSYLVANIA.

PROPELLION MECHANISM.

1,224,120.

Specification of Letters Patent Patented Apr. 24, 1917.

Application filed October 12, 1909, Serial No. 522,250. Renewed March 21, 1917. Serial No. 156,456.

To all whom it may concern:

Be it known that I, HORACE M. CAKE, a citizen of the United States, and a resident of the city of Philadelphia, in the State of Pennsylvania, have invented certain new and useful Improvements in Propulsion Mechanism, of which the following is a specification.

This invention relates broadly to mechanism for propelling water or aero-craft and specifically to a mechanism whereby a single source of power may drive two propellers.

The principal object of this invention is to provide a mechanism wherein two propellers may be driven from a single source of power and each propeller transmit one-half the total power received.

A further object of the invention is to provide a mechanism wherein two propellers of different size may be driven from a single source of power, in such manner that the effective speed of each propeller is automatically determined.

Another object of the invention is to provide a mechanism wherein two propellers, each having blades set at different angles with reference to the other propeller, may be automatically driven at their most effective speed.

A still further object of the invention is to provide a mechanism for propelling boats, etc., the mechanism being so constructed that the power delivered in propelling the boat will be utilized with a minimum loss, due to "churning", etc.

A still further object of the invention is to provide propelling means for water craft, which comprises tandem screws, axially aligned, both revolving in the same direction, the speed of each screw being dependent upon the resistance offered by the water to the other screw.

This invention which is believed to be broadly new, may be susceptible of structural changes, but a preferred form will be herein described and shown in the accompanying drawings in which:

The figure is a plan view showing part of the mechanism in section.

In this invention the driving shaft, which may be connected to any type of engine or motor, terminates in a transmission head which carries on its periphery compensating pinions, or beveled gears. These pinions mesh on one side with a beveled gear wheel which is fixedly secured to a short stub

shaft, on the end of which shaft is mounted a propeller. The compensating pinions mesh on the other side with a beveled gear mounted upon the engine shaft and which is rigidly attached to a gear casing that terminates in an elongated tubular shaft encompassing the short stub shaft. The end of the tubular shaft also carries a propeller. In my preferred form, the propeller carried by the tubular shaft is larger in size than the propeller carried by the stub shaft.

Referring particularly to the drawing, the engine shaft 1 carries rigidly fixed thereon a transmission head 2. Compensating gears, or beveled pinions 3, are mounted upon the periphery of the transmission head by means of ball-bearings 4, which are carried upon stud bolts 5. In the drawing, I have illustrated the mechanism as showing two compensating gears; it may be desirable to use three or more compensating gears, as this would more evenly transmit power from the transmission head. The compensating gears 3 mesh with an annular beveled gear 6 which is formed upon a face plate 7. The face plate 7 is bolted to a casing member 8 by means of stud bolts 9. The compensating gears 3 mesh upon their opposite side with a beveled gear 10, which is rigidly attached to a stub shaft 11. The outer end of the stub shaft 11 carries a propeller 12, which is detachably mounted thereon by means of check nuts 14. The casing member 8 terminates in a tubular shaft 13 which is mounted to rotate upon the stub shaft 11. This tubular shaft carries at its outer extremity a propeller 16 which is detachably mounted thereon by means of check nuts 17 and a bushing casing 18. The bushing casing 18 is arranged to compress packing material 19 in order to prevent water from entering between the shafts 11 and 15. A ball-bearing 20 is arranged between the casing member 8 and the beveled gear 10. A similar ball-bearing 21 is arranged on the opposite side of the transmitting head 2, between the face plate 7 and the engine shaft 1. For the sake of clearness, the thrust bearing and the bearing in the hull of the vessel have been omitted, since these two bearings do not form a part of the herein described invention.

The operation of the device is as follows:—Power is transmitted through the engine shaft 1 to the transmission head 2, and thence by means of the compensating

gears 3, to the beveled gear 10 and the face plate 7. As the face plate 7 forms a part of the casing member 8 and the tubular shaft 15, power transmitted through the 5 face plate is delivered to the large propeller 16, and similarly as the beveled gear 10 is attached to the stub shaft 11, power transmitted to the beveled gear is delivered to the small propeller 12. Thus it will be seen 10 that the compensating gears 3 perform a double function namely, first, that of transmitting power from the engine shaft to the two propellers, and secondly that of forming compensating means whereby a condition of equilibrium is maintained between 15 the two propellers 12 and 16. The large propeller will normally offer a greater resistance to the medium through which it is revolving than will the small propeller, presuming 20 that both are revolving at the same rate of speed. Since the compensating gears 3 have a function of being an equalizing pivot, it will be seen that the large propeller will be slowed down in its number of revolutions, and the small propeller will be correspondingly increased until the transmitted 25 force is equal on both sides of the compensating gears 3. This relationship automatically divides the effective propulsion power, 30 equally between the two propellers, irrespective of the size of the propellers or the pitch of their blades, and thus it will be seen that the given power on the engine shaft will deliver an effective power to the propellers 35 equally distributed between them in such manner that each propeller is operating at its greatest efficiency.

Furthermore, this invention provides that both propellers be rotated in the same direction. This fact will tend to reduce the "churning," which is merely power lost in disturbing water and not effectual in propelling the boat, because of the fact that both propellers are passing through the 45 water in the same direction. The application of this invention applies equally well to propellers used in aero-crafts. I desire it to be understood that my invention covers any craft that is propelled by means of 50 screw propellers.

As many changes could be made in the above described structure and many widely different embodiments of this invention could be made without departing from the 55 scope thereof, the definite matter contained in the above description and shown in the accompanying drawings, is to be taken as illustrative and not in its limiting sense.

I desire it also to be understood that the 60 language used in the claims is intended to cover all generic and specific features of this invention herein described, and all statements of the scope of the invention which as a matter of language might fall therebetween.

Having described my invention what I claim is:—

1. In a propulsion mechanism in combination, a driving shaft, a cylindrical driven shaft, a tubular shaft surrounding said cylindrical shaft, compensating means operatively connecting said driving shaft with both the cylindrical shaft and the tubular shaft to drive the cylindrical shaft and the tubular shaft in the same direction, and 70 propellers on both driven shafts.

2. In a propulsion mechanism in combination, a driving shaft, a transmission head, compensating gears carried by said transmission head, a cylindrical driven shaft, a 75 tubular driven shaft, operative means connecting said tubular shaft with said compensating gears, operative means connecting said cylindrical shaft with said compensating gears to drive said cylindrical shaft in 80 the same rotative direction as the tubular shaft, and propellers on both driven shafts.

3. In a propulsion mechanism in combination, a driving shaft, two driven shafts axially aligned and axially aligned with the 85 driving shaft, compensating means operatively connecting said driving shaft with said driven shafts to drive both the said driven shafts in the same direction, and screw propellers on both driven shafts. 95

4. In a propulsion mechanism in combination, a driving shaft, a transmission head carried by said driving shaft, compensating gears upon said transmission head, a face plate carrying thereon a beveled gear in engagement with the compensating gears, a tubular shaft, a casing integral with said tubular shaft, said face plate being secured to and comprising a closure for said casing, a cylindrical shaft within said tubular shaft, 100 a beveled gear carried upon said cylindrical shaft and in engagement with the compensating gears, a propeller on said tubular shaft, and a propeller on the cylindrical shaft. 105

5. In a propulsion mechanism in combination, a driving shaft, a transmission head carried by said driving shaft, compensating gears, beveled gears engaging said compensating gears at diametrically opposite points, a tubular shaft, a propeller on said tubular shaft, a cylindrical shaft mounted within said tubular shaft, a propeller carried by said cylindrical shaft, one of said beveled gears being operatively connected with said tubular shaft, and the other of said beveled gears being operatively connected with said cylindrical shaft. 115

6. A propulsion mechanism including a 120 driving shaft, two screw propellers mounted in axial alignment and means intermediate said driving shaft and said propellers to drive both propellers in the same direction in such manner that the speed of either of said propellers is dependent upon the re- 125

sistance offered to the other propeller, both of said screw propellers rotating about the axis of the driving shaft.

7. A propulsion mechanism including a driving shaft, two driven shafts, screw propellers on said shafts, said propellers being mounted in tandem and means intermediate said driving shaft and said driven shafts to drive both driven shafts in the same direction and to equalize the effective force delivered by each propeller.

8. A propulsion mechanism including a driving shaft, two driven shafts in axial alinement and in axial alinement with the driving shaft, screw propellers carried by said driven shafts, and compensating gears intermediate said driving shaft and said driven shafts whereby both propeller shafts are driven in the same direction and the force delivered by the driving shaft is automatically and equally divided between the said propellers when the mechanism is in normal operation.

9. A propulsion mechanism including a driving shaft, a cylindrical driven shaft, a tubular driven shaft surrounding said cylindrical driven shaft, propellers carried upon said driven shafts, and means intermediate said driving shaft and said driven shafts whereby the driven shafts are rotated in the same direction and the force delivered by each propeller is automatically equalized.

10. A propulsion mechanism including a driving shaft, two driven shafts, screw propellers on said shafts, said propellers being mounted in tandem and means intermediate said driving shaft and said driven shafts to drive both the driven shafts in the same direction and to equalize the effective force delivered by each propeller, the driving shaft and driven shafts being in axial alinement.

11. A propulsion mechanism including a driving shaft, two screw propellers mounted in tandem, means intermediate said driving shaft and said propellers whereby both propellers are rotated in the same direction and the speed of either of said propellers is made dependent upon the resistance offered to the other propeller.

12. In a propulsion mechanism in combination, a driving shaft, two driven shafts, screw propellers carried on said driven shafts and compensating means operatively connecting said driving shaft and said driven shafts to drive both driven shafts in the same direction, the blades of said screw propellers being pitched in the same direction, the driving shaft and both driven shafts being in axial alinement.

13. In a propulsion mechanism in combination, a driving shaft, a transmission head carried on said driving shaft, compensating gears upon said transmission head, a face plate carrying thereon a beveled gear in en-

gagement with the compensating gears, a tubular shaft, a propeller on said tubular shaft, a casing attached to said tubular shaft, said face plate being secured to and comprising a closure for said casing, a cylindrical shaft mounted within said tubular shaft, a propeller carried upon said cylindrical shaft, and a beveled gear on the cylindrical shaft and in engagement with the compensating gears, the driving shaft, the tubular shaft and the cylindrical shaft all being in axial alinement.

14. A propulsion mechanism including a driving shaft, a cylindrical driven shaft, a tubular driven shaft surrounding said cylindrical driven shaft, propellers carried upon said driven shafts, means intermediate said driving shaft and said driven shafts whereby both driven shafts are rotated in the same direction and the force of each propeller is automatically equalized.

15. In a propulsion mechanism in combination, a driving shaft, a transmission head, compensating gears carried by said transmission head, a cylindrical shaft, a tubular driven shaft, operative means connecting said tubular shaft with said compensating gears, operative means connecting said cylindrical shaft with said compensating gears to drive said cylindrical shaft in the same rotative direction as said tubular shaft is driven, a propeller carried upon said tubular shaft and a propeller carried upon said cylindrical shaft, the driving shaft, the tubular shaft and the cylindrical driven shaft all being in axial alinement.

16. In a propulsion mechanism in combination, a driving shaft, a cylindrical driven shaft, a tubular shaft surrounding said cylindrical shaft, and compensating means operatively connecting said driving shaft with both the cylindrical shaft and the tubular shaft whereby both shafts are driven in the same direction, a propeller mounted upon said tubular shaft and a propeller mounted upon said cylindrical shaft.

17. A propulsion mechanism including a driving shaft, two driven shafts, screw propellers mounted in tandem on said driven shafts, compensating gears intermediate said driving shaft and said driven shafts whereby both driven shafts are rotated in the same direction and the force delivered by the driving shaft is automatically and equally divided between said propellers when the mechanism is in normal operation.

18. In a propulsion mechanism in combination, a driving shaft, a transmission head carried by said driving shaft, compensating gears carried on the transmission head, beveled gears engaging said compensating gears on diametrically opposite sides, a tubular shaft, a propeller on said tubular shaft, a cylindrical shaft mounted within said tubular shaft, a propeller carried on

- 4
- 5 said cylindrical shaft, one of said beveled gears being operatively connected with said tubular shaft, and the other of said beveled gears being operatively connected with said cylindrical shaft, the driving shaft, the tubular shaft and the driven cylindrical shaft all being axially alined.
- 10 19. A propulsion mechanism including two screw propellers mounted in tandem, a driving shaft and compensating means whereby both propellers are driven in the same direction.
- 15 20. A propulsion mechanism including two screw propellers mounted in tandem, a driving shaft, means for driving both propellers in the same direction and for automatically equalizing the amount of work done by each propeller.
- 20 21. A propulsion mechanism including a plurality of screw propellers revolving in the same direction, all of said propellers being mounted in tandem to rotate about a common axis of rotation, a driving shaft, and means for causing the effective working load to be automatically distributed equally among said propellers.
- 25 22. In a propulsion mechanism in combination, a driving shaft, two concentric driven shafts, screw propellers having blades pitched in the same direction carried by said driven shafts, and means for taking power from each side of said driving shaft and delivering said power to each side of said driven shafts.
- 30 23. In a propulsion mechanism in combination, a driving shaft, a transmission head, compensating gears, screw propellers both on one side of said compensating gears, the blades of said screw propeller being pitched in the same direction, means for taking power from each side of said compensating gears and transmitting said power to said propellers to drive said propellers in the same rotative direction.
- 35 24. A propulsion mechanism including a driving shaft, a transmission head, compensating gears carried by said transmission head, a cylindrical driven shaft, a propeller on said cylindrical shaft, a tubular shaft, a propeller on said tubular shaft, said tubular shaft and said cylindrical shaft both being on one side of said transmission head, a beveled gear operatively connected with said cylindrical shaft, said beveled gear being on the same side of the transmission head as are the propellers, and a second beveled gear on the opposite side of the said transmission head, and operatively connected with the said tubular shaft.
- 40 25. In a propulsion mechanism in combination, a driving shaft, a transmission head carried on said driving shaft, compensating gears upon said transmission head, a face plate carrying a beveled gear, a tubular shaft, a cylindrical shaft mounted within
- 45 50 55 60 65 said tubular shaft, a propeller on said tubular shaft and a propeller on said cylindrical shaft, a beveled gear carried upon said cylindrical shaft and a casing operatively connected with said face plate and said tubular shaft, said casing inclosing the said compensating gears and the beveled gear on the cylindrical shaft.
- 70 26. In a propulsion mechanism in combination, a driving shaft, a cylindrical driven shaft, a tubular shaft surrounding said cylindrical shaft, rotative means operatively connecting said driving shaft with both the cylindrical and the tubular shafts to drive said cylindrical shaft and said tubular shaft in the same direction, pivotal means about which said rotative means rotate, the axis of said pivotal means being at right angles to the axis of said driving shaft, a propeller on said cylindrical shaft, and a propeller on said tubular shaft.
- 75 27. In a propulsion mechanism in combination, a driving shaft, a transmission head, compensating gears mounted upon said transmission head, a cylindrical driven shaft, a tubular shaft surrounding said cylindrical shaft, the axis about which said compensating gears rotate being ninety degrees to the axis of said driving shaft, operative means connecting said tubular shaft with said compensating gears, operative means connecting said cylindrical shaft with said compensating gears, a propeller mounted upon said tubular shaft, and a propeller mounted upon said cylindrical shaft.
- 80 85 90 95 100 105 110 115 120 125 130 28. In a propulsion mechanism in combination, a driving shaft, a transmission head carried by said driving shaft, compensating gears rotatively mounted upon said transmission head, the axis about which said compensating gears rotate being at ninety degrees to the axis of said driving shaft, a face plate carrying thereon a beveled gear engaging the compensating gears, a tubular shaft, a casing integral with said tubular shaft, said face plate being secured to and comprising a closure for said casing, a cylindrical shaft mounted within said tubular shaft, a beveled gear carried by said cylindrical shaft and also engaging the compensating gears, a propeller on said tubular shaft, and a propeller on said cylindrical shaft.
29. A propulsion mechanism including a driving shaft, two driven shafts axially alined, screw propellers mounted in tandem on said driven shafts, rotative means intermediate said driving shaft and said driven shafts to equalize the effective force delivered by each propeller, said rotative means being adapted to rotate upon an axis that is substantially at ninety degrees to the axis of the driven shafts.
30. A propulsion mechanism including a driving shaft, two driven shafts axially

aligned, screw propellers mounted in tandem on said driven shafts, and rotative means intermediate said driving shaft and said driven shafts to equalize the effective force delivered by each propeller, said rotative means being adapted to rotate upon axes which are substantially ninety degrees to

the axis of said driven shafts, the driving shaft and the driven shafts being in axial alignment.
